 Ill., a corporation of Delaware

Application July 5, 1935, Serial No. 29,863

14 Claims. (CL 179—27)

This invention relates to telephone systems. It is concerned particularly with telephone systems including a main exchange and a private branch exchange in which the local calls and calls outgoing from branch exchange subscribers are handled through automatic switches, while calls incoming to the branch exchange are intercepted and completed under the control of an attendant operator. The main object of the invention is concerned with the production of new and improved features of operation which enable the inter-exchange service to be handled more satisfactorily by means of a minimum of relatively simple equipment.

15 GENERAL DESCRIPTION

As is well known, local service in a private automatic branch exchange is handled through dial-controlled automatic switches; calls from branch exchange lines to the main exchange are handled over inter-exchange trunk lines seized by the automatic switching apparatus in the branch exchange responsive to the dialling of the main-exchange designation; while calls incoming from the main exchange to the branch exchange are intercepted by the branch exchange operator, who directs them to the appropriate or desired branch exchange lines.

From the standpoint of handling incoming calls, attended private automatic branch exchanges may be divided into two classes: (1) private automatic branch exchanges in which the incoming calls are completed through automatic switching apparatus controlled by the branch-exchange attendant or operator, and (2) private automatic branch exchanges in which incoming calls are extended manually through a manual switchboard presided over by the branch exchange operator. The present disclosure has to do with a private automatic branch exchange of the second of the above-mentioned classes.

The private automatic branch exchange disclosed herein contains desirable features, including the following:

1. In order to insure the secrecy of conversation against accidental or intentional invasion or "eavesdropping" by the branch-exchange operator, arrangements are provided such that a warning tone-signal is transmitted over a connection established through the operator's switchboard in the event that the operator throws the talking key of a cord circuit over which a conversation is taking place, this arrangement being controlled through the answer-

ing supervisory relay and contacts of the associated talking key.

2. In order to prevent the operator from plugging in to the manual-switchboard multiple of the local subscriber's line and overhearing a conversation in progress, and also to prevent the operator from inadvertently interfering with a dialling operation in progress in the event that she makes connection with a busy local line, the tip and ring conductors of the local plug of each 5 of the cord circuits are maintained normally disconnected from the main part of the cord circuit, and the connecting up of the normally disconnected talking conductors is made dependent upon the operation of an idle-test relay over the 10 sleeve conductor of an idle subscriber's line. By this arrangement, the operator may insert her plug in the jack of a busy line and still be unable to hear the conversation over the line and be prevented from interfering with the progress of a 15 partially completed connection, because the tip and ring strands of the local plug of the cord circuit are maintained open.

3. In order to prevent the operator from defeating the arrangement set forth in the preceding paragraph by employing the trunk plug of a cord to listen in on a busy connection, contacts controlled jointly by the sleeve-connected 25 trunk supervisory relay and the talking key of the cord circuit bring about the transmission of 30 the aforementioned warning tone-signal to the operator's headset conductors and thus to the line being intruded upon thereby notifying the operator that her intended intrusion is not going unnoticed, and notifying the two subscribers of 35 the busy connection that the secrecy of their conversation is being invaded.

4. In order to provide for the making of a more reliable busy test through the bringing of the tip and the plug into engagement with the sleeve 40 of the jack, circuit arrangements have been provided to respond to the operation of a busy-test relay (over the tip of the plug from guarding potential encountered on the sleeve of the jack of a busy line) to bring about the application of 45 a tone signal to the operator's headset conductors. By this simple provision, the operator need only make sure that the tip of plug makes firm contact with the sleeve of the jack. Under this condition, the absence of a tone signal in the operator's receiver indicates that the line is idle. This same arrangement operates in conjunction 50 with a previously mentioned feature to secure correct performance in the event that the operator inadvertently or intentionally fails to make 55

- the tip-sleeve busy test and inserts the plug into the jack of a busy line. The above busy-test relay then operates over the tip conductor of the busy line to cause the application of a busy-tone signal to the operator's headset conductors, while the tip and ring conductors of the plug are maintained disconnected from talking conductors of the cord because of the absence of an idle-indicating potential on the sleeve element of the jack. The busy-test relay is preferably of high impedance, so that its connection to the tip contact of a jack will not interfere with the progress of a connection being set up automatically under the control of a dial.
5. In order to provide the branch exchange operator with a ready means of making connection with busy branch-exchange lines for the purpose of offering incoming calls, an offering cord and plug are attached to the operator's headset conductors, through which the operator may extend connection to any local line multipled into the manual switchboard. But, the above mentioned warning tone-signal arrangement is associated also with the offering cord so that the insertion of the offering cord into the jack of the local line results in the application of warning tone-current to the operator's headset conductors and to the conductors of the local line connected with so as to warn the subscribers 30 that the operator is telephonically connected with the connection.
6. In order to enable a local subscriber engaged in an inter-exchange conversation to obtain additional information, for example, each of the inter-exchange trunk lines terminating at the branch exchange has a branch connection extending to the automatic switchboard, together with switching means controllable at will over a local line to switch the local line temporarily 40 into connection with the automatic switchboard so that the subscriber may set up a local connection automatically to another local line and then later switch the connection back to the inter-exchange trunk line.
7. An additional desirable feature is found in the arrangement controlled partly through a local cord and partly from an inter-exchange trunk circuit for disconnecting both plugs of a local cord when the local subscriber involved in 50 a call incoming from the main exchange replaces his receiver, thereby freeing the branch-exchange end of the trunk line immediately as well as immediately freeing the local line for further use, pending the taking down of the local cord by the branch exchange operator.
8. In order to render completely effective the aforementioned arrangement for preventing the operator from either eavesdropping or interfering unintentionally with the progress of calls being 60 set up automatically from local substations, a cut-off relay has been added to each of the two-way inter-exchange trunk lines, which relay operates when the two-way trunk line is seized automatically in the branch exchange to cut off 65 the switchboard extension of the trunk line so that the corresponding jack at the operator's switchboard is telephonically disconnected.

Description of drawings

- 70 Referring now to the accompanying drawings, comprising Figs. 1 to 4, they show by means of the usual circuit diagrams a sufficient amount of the equipment involved in a telephone system embodying the invention to enable the invention 75 to be understood.

Fig. 1 shows diagrammatically local lines associated with substations A and B, line switches LS1 to LS4 of the automatic switchboard; the automatic selector S1, and the connector C1; the cord circuit CC at the manual switchboard, the line jacks LJ1 and LJ2, associated with the lines of substations A and B; and the trunk jack TJ;

Fig. 2 shows the operator's position equipment which is common to several cord circuits (such as the cord circuit CC, Fig. 1), together with the offering cord which terminates in the offering plug OP;

Fig. 3 shows the one-way outgoing trunk line T1 and the associated trunk circuit TC1; and

Fig. 4 shows the two-way inter-exchange trunk line T2 and associated trunk circuit TC2.

In Fig. 1, the lines from the automatic substations A and B extend as indicated to the line switches LS2 and LS1, respectively. These line switches may be of any desired construction, being indicated only diagrammatically in the drawings, as are the similar line switches LS3 and LS4.

The line switches LS1—LS4 have common access to selectors, of which the selector S1 is one. The selector S1 may be of the usual vertical and rotary type, having its back contacts arranged in horizontal rows or levels. The selector S1 has access by way of one of its levels of bank contacts to the connector C1, which is one of a group of connectors through which connection may be extended to the 100-line group containing the line of substation B. On another of its levels, the selector S1 has access to the trunk lines of Figs. 3 and 4. The one-way trunk line of Fig. 3 is indicated as being a first-choice trunk line, while the two-way trunk line of Fig. 4 is indicated as being taken into use only after the first-choice trunk lines have been tested and found to be busy. This is in accordance with the usual practice of reserving the more expensive two-way trunk lines until all of the less expensive one-way trunk lines have been taken for use.

It is to be noted that the line jack LJ1 is a manual-switchboard multiple of the called multiple of the line of substation A at the automatic switchboard, while the line jack LJ2 is a similar multiple of the called multiple of the line of substation B. It will be noted further that the trunk jack TJ is a manual-switchboard extension of the trunk T2, Fig. 4, by way of the trunk circuit TC2, and that the line switches LS3 and LS4 are associated respectively with the trunk circuits TC1 and TC2. It may be mentioned at this point that it is through line switches such as LS3 and LS4 that transfer service is made available to local subscribers involved in inter-exchange conversation, as will be pointed out more in detail hereinafter.

At the cord circuit CC, Fig. 1, the trunk plug TP is the one designed to be inserted into trunk jacks such as TJ, while the local plug LP is the one to be inserted into a local jack, or line jack, such as LJ1 and LJ2. The cable 200 is a multiple cable which multiples the common conductors 221—230 (associated with the position equipment of Fig. 2) with the various cord circuits, of which the cord circuit CC, Fig. 1, is one.

Detail description

The disclosure having been described generally, a detailed description of the operations involved in setting up and handling the several kinds of connections will now be given. For this purpose it will be assumed first that the subscriber at sub- 70 75 75

station A, desiring to converse with a main exchange subscriber, removes his receiver and dials the designation of the main exchange.

Outgoing call over a one-way trunk

When the receiver (not shown) is removed at substation A, the line switch LS2 operates in the usual manner to select an idle selector, the selector S1, for example. Upon the seizure of the selector S1, the automatic switchboard equipment is in readiness for the subscriber at substation A to dial the designation of the main exchange.

When the designation of the main exchange (the digit 0, for instance) is dialled, the selector S1 raises its wipers opposite the level of bank contacts containing the main-exchange trunk lines, whereupon the wipers are rotated over the bank contacts in search of an idle trunk line. Under the assumption that the trunk line T1, Fig. 2, is idle, the wipers of the selectors S1 come to rest on the bank contacts from which the conductors 309, 310, and 311 extend to the trunk circuit TC1, associated with the trunk line T1, Fig. 3.

Upon the seizure of the trunk circuit TC1, line relay 304 thereof, which is connected to conductors 309 and 310 through the right-hand windings of repeating coil 303 and the windings of the differential transfer-control relay 308, energizes over the line of substation A. Upon energizing, line relay 304 places a bridge across the conductors of the trunk line T1 at its upper contacts through the left-hand windings of repeating coil 303 and the resistor 315, which is shunted around the talking condenser associated with the left-hand repeating-coil windings. The closure of this bridge prepares automatic switching apparatus in the main exchange for further dialling operations in the event that the main exchange is an automatic exchange, while, if instead the main exchange is a manual exchange, the bridging of the trunk line T1 results in the lighting of the usual line lamp at the operator's switchboard.

As a further result of its energization, line relay 304 closes a circuit for release relay 306 at its inner armature, whereupon relay 306 operates and prepares a locking circuit for transfer relay 305 at its lower armature, at the same time applying a holding potential to conductor 311 at its upper armature. The holding potential thus applied to conductor 311 is effective to maintain the selector S1 and the line switch LS2, Fig. 1, operated until the receiver is replaced at the calling substation A.

When the connection over the trunk line T1 has been set up through the main exchange switchboard to the desired line and an answer has been secured, conversation may take place between the line of substation A and the called line through the line switch LS2, the selector S1, the trunk circuit TC1, and the trunk line T1.

When the conversation is finished, the subscriber at substation A replaces his receiver, whereupon line relay 304 restores and opens the bridge across the conductors of the trunk line T1 at its upper contacts, thereby bringing about the release of the automatic switching equipment in the main exchange in the event that the main exchange is an automatic exchange, or bringing about the lighting of the usual disconnect lamp at the manual switchboard in the main exchange, provided the main exchange is a manual exchange.

The deenergization of line relay 304 brings

about the deenergization of relay 306, whereupon holding potential is removed from conductor 311, permitting the release of the selector S1 and line switch LS2 to take place.

Transfer service through the one-way trunk circuit TC1

Let us assume now that the subscriber at substation A has set up an outgoing connection by way of the lineswitch LS1 and the selector S1 over the trunk circuit TC1 and the trunk T1, and that during the conversation the subscriber at substation A desires to converse momentarily with another local branch exchange subscriber, to obtain additional information, for example. For this purpose, the subscriber at substation A after requesting the main exchange subscriber to hold the line for a moment, momentarily depresses his grounding transfer-control push button P1, thereby applying ground potential momentarily to one of the conductors of his line. This momentary application of ground potential to a conductor of the line of substation A unbalances the current-flow through the two windings of the differential transfer-control relay 308 sufficiently to cause an operation of relay 308. Upon operating, relay 308 closes a circuit for the inefficient upper winding of the two-step transfer relay 305, whereupon relay 305 energizes just sufficiently to close its lightly adjusted first-step contacts, the inner lower contacts of the relay. The actuation of these contacts closes a locking circuit for both windings of relay 305 in series, through contacts controlled by the armature of unlock relay 307 and the lower contacts of release relay 306. No current, however, flows through the lower winding of relay 305 for the time being because the initial circuit for the upper winding of relay 305 is an effective shunt around the lower winding of the relay.

When the push-button P1 is released, transfer-control relay 308 restores responsive to the restoration of the normal balanced condition of current flow through its windings. The initial circuit for the lower winding of relay 305 is thereby opened, whereupon the locking circuit for both windings of the relay in series becomes effective, and relay 305 operates fully to seize the lineswitch LS3, Fig. 1, by way of conductors 312-314. At its upper armature, transfer relay 305 places a shunt around the upper contacts of the line relay 304 so as to maintain the trunk line T1 continuously bridged, and at its lower armature it shifts the contacts of transfer control relay 308 from its own winding to the winding of unlock relay 307.

The line switch LS3 operates over the calling line (A) and over conductors 312 and 313 in the usual manner to select an idle selector, similar to the selector S1. Ground potential is placed on conductor 314 of the line switch LS3 by the seized selector to close a holding circuit over conductor 314 and through the inner upper contacts of transfer relay 305 for release relay 306, thereby maintaining this relay operated after line relay 304 has fallen back, which it does upon being disconnected at the transfer contacts of relay 305.

The subscriber at substation A now proceeds to dial the number of the desired local line, whereupon the connection is extended through the automatic switchboard to the desired line and conversation may take place in the usual manner.

After the calling local subscriber at substation A has obtained the desired information from the

called local subscriber, he again momentarily depresses the push button P_1 , again bringing about a momentary operation of transfer-control relay 308. When it operates at this time, transfer control relay 308 closes a circuit through the operated lower armature of transfer relay 305 for unlock relay 307. Unlock relay 307 now operates and extends its operating potential at its lower armature to the locking circuit of transfer relay 305, 5 at the same time disconnecting the locking circuit of transfer relay 305 from ground potential at the lower contacts of release relay 306. Then, when transfer-control relay 308 restores (when P_1 is released), it opens the circuit of relay 307 10 and the locking circuit of relay 307. Relay 305, being slow-acting, remains operated for a short interval after the circuit is opened, so that transfer relay 305 is permitted to fall back and open a point in its locking circuit before relay 307 15 restores.

Upon restoring, transfer relay 305 disconnects conductors 312, 313, and 314, permitting the connection set up through the lineswitch LS3 to clear out. 20 Line relay 304 now operates again over the line of substation A and again takes over the control of release relay 306 and the control over the bridge established across the outgoing trunk line T_1 . A moment later, the slow-releasing unlock relay 307 restores. Relay 307, it is noted, maintains the trunk line T_1 bridged during the transition period following the restoration of relay 305 and the resulting reoperation of line relay 304. 25

The interrupted conversation between the subscriber at substation A and the main exchange subscriber reached over the outgoing trunk line T_1 may now be resumed.

It will be appreciated, of course, that the subscriber at substation A may, if he so desires, again 30 interrupt the conversation with the main exchange subscriber and again transfer his connection over to the line switch LS3 for the purpose of setting up another local inquiry connection in the manner described hereinbefore.

45 When the conversation is completed the subscriber at substation A replaces his receiver, whereupon the interexchange connection is cleared out as before explained.

50 An outgoing call over a two-way trunk

For the purpose of explaining the operation of the trunk circuit TC2, Fig. 4, when it is seized in the branch exchange in an outgoing call, it will be assumed that the subscriber at substation A 55 makes an outgoing call by way of the selector S_1 , for example, at a time when all of the one-way trunk lines, such as the one shown in Fig. 3, are in use and that the trunk line T_2 , Fig. 4, is the first one found to be idle by the selector S_1 as it 60 rotates over the trunk-line contacts. That being the case, the trunk circuit TC2, Fig. 4, is seized by the selector S_1 over conductors 421—423, whereupon line relay 404 of the trunk circuit TC2 energizes over the line of substation A and over 65 conductors 421 and 422. At its upper contacts, line relay 404 bridges the conductors of the trunk line T_2 through the left-hand windings of repeating coil 403 and resistor 413, while at its lower armature it closes a circuit for release relay 405. 70 Release relay 405 thereupon operates and places ground potential on conductor 423 at its upper armature, thereby providing a holding circuit for the selector S_1 and the line switch LS2. Release relay 405 also disconnects the ring-up relay 406 75 from in bridge of the conductors of the trunk line

T2, while at its inner upper armature it prepares a locking circuit for transfer relay 410.

At the lower armature of release relay 405, a circuit is closed over 427 for busy lamp 123 to notify the operator that the trunk is in use.

5 Jack-cut-off relay 412, whose lower winding is normally in series with conductor 421, energizes over conductor 421 and over the calling line, in series with line relay 404. Upon energizing, relay 412 closes a locking circuit for its upper winding to the grounded release trunk conductor 423, while at its upper and lower armatures it disconnects conductors 424 and 425 which lead to the trunk jack T_2 . The trunk jack T_2 is therefore no longer in multiple of the trunk circuit TC2, and 15 will be maintained disconnected for the duration of the call.

The lower winding of jack-cut-off relay 412 is by-passed at the lower armature of the relay, so as to afford a better talking and dialling circuit.

20 The desired connection is completed in the main exchange, either manually or responsive to further dialling on the part of the subscriber at substation A, depending upon whether the main exchange is a manual exchange or an automatic exchange. In the event that the main exchange is an automatic exchange, the dialling impulses are repeated by line relay 404 at its upper contacts, as in the case of line relay 304 of trunk circuit TC1, Fig. 3.

25 Transfer service through the two-way trunk Circuit TC2

In the event that the subscriber at substation A desires to transfer the connection back to the 35 automatic switchboard for the purpose of setting up a local inquiry call, he proceeds as described in connection with the call previously set up through the trunk circuit TC1, Fig. 3, in which case relays 411, 410, and 409 operate as described 40 in connection with relays 308, 305, and 307. It is to be noted that the transfer connection in this case is over conductors 413—415 to the line switch LS4, Fig. 1.

45 It is to be noted further that relays 409 and 410 cooperate at their upper contacts to maintain the trunk T_2 bridged during the time the connection is transferred away from the trunk T_2 and pending the reoperation of line relay 404.

When the receiver is replaced at substation A 50 at the end of the inter-exchange conversation, line and release relays 404 and 405 restore, whereupon the removal of ground potential from conductor 423 at the upper contacts of release relay 405 results in the clearing out of the automatic 55 switches LS2 and S_1 .

60 Handling an incoming call

For the purpose of describing how incoming calls are handled, it will be assumed that the trunk 60 line T_2 , Fig. 4, is seized in the main exchange in a call for a subscriber of the branch exchange.

When the trunk line T_2 is seized in the main exchange, ringing current is projected thereover in the usual manner, operating ring-up relay 406 65 which is bridged across the conductors of the trunk line T_2 through the associated condenser. Relay 406 closes a circuit for call relay 407, which relay responds and closes a locking circuit at its inner upper armature through contacts of release 70 relay 405. Call relay 407 also prepares a circuit for hold relay 408 at its inner lower armature, while at its upper armature it places ground potential on conductor 423 so as to mark the trunk 75

line engaged immediately at the selectors such as S1, Fig. 1.

5 Relay 407, at its inner lower armature, closes a circuit over conductor 421 for busy lamp 123 at the trunk jack TJ, while at its lower armature it closes a circuit over conductor 428 for the call lamp 124, thereby notifying the operator that a call has been received from the main exchange.

10 The branch exchange operator responds to the lighted condition of the call lamp 124 by inserting the trunk plug of a cord circuit, trunk plug TP of cord circuit CC, for example, into the trunk jack TJ.

15 When the trunk plug TP is inserted into the jack TJ, the strands of the cord circuit CC are bridged across conductors 424 and 425 operating the line relay 404 in the trunk circuit TC2 over the supervisory bridge in the cord circuit CC, which bridge includes contacts controlled by the lower armature of connecting relay 106, contacts 20 of the answering supervisory relay 105, and resistor 114. Upon operating through the cord circuit CC, line relay 404 at its lower armature removes ground potential from sleeve conductor 426 25 of the trunk jack TJ, thereby preventing false operation of the supervisory and release timer relay 108 in the cord circuit CC. Line relay 404 also closes a direct current bridge across the conductors of the trunk T2 at its upper contacts, thereby causing the ringing condition to be terminated in the main exchange and giving answering supervision.

30 Hold relay 408 operates through the lower contacts of the operated relays 404 and 407 to bridge the trunk line T2 at its upper contacts independent of the upper contacts of line relay 404.

35 Release relay 405 responds to the operation of line relay 404 and disconnects ring-up relay 406 at its inner lower armature; makes an additional application of ground potential to conductor 427 40 at its lower armature; makes an additional application of ground potential to release trunk conductor 423 at its upper armature; and at its inner upper armature it opens the locking circuit of call 45 relay 407, at the same time closing a locking circuit for the upper winding of the operated hold relay 408 and preparing a locking circuit for transfer relay 410. Relay 408 is therefore maintained operated throughout the remaining time 50 of the incoming connection under the control of release relay 405 so as to maintain the state of answered supervision over the trunk line T2 at its upper contacts.

Upon the falling back of call relay 407, the call 55 lamp 124 at the trunk jack TJ is extinguished at the lower contacts of the relay, but conductors 423 and 427 remain grounded at contact of release relay 405, thereby maintaining the trunk circuit TC2 guarded at the automatic switchboard and maintaining busy lamp 123 lighted at the trunk 60 jack TJ.

65 In order to converse with the calling subscriber, the operator now throws her key K1 of the cord circuit CC into talking position, thereby operating the right-hand contacts of the key. The tone lead 225 is connected up at the upper contacts of the talking key; the hold lead 222 is connected up at the lower contacts of the talking key, while at the middle contacts of the talking key the test lead 221 is brought into connection with the 70 lower winding of connect relay 106. The test conductor 221 is normally grounded at the upper contacts of guard relay 201. Assuming guard relay 201 to be in normal position at this time, the upper winding of connect relay 106 of the cord

75 circuit CC is energized over conductor test 221, whereupon connect relay 106 operates and closes a holding circuit for its lower winding at its inner lower contacts, through the lower contacts of the talking key, and over hold conductor 222 in series with guard relay 201, Fig. 2. Guard relay 201 thereupon operates in series with the lower winding of connecting relay 106 and removes ground potential at its upper contacts from test conductor 221 to insure that no further connect relay such as 106, Fig. 1, is operated until the operator restores the key K1 and permits connect relay 106 and guard relay 201 to restore.

80 As further results of its operation, connect relay 106 connects the tip and ring conductors 223 and 224 of position equipment PE with the corresponding conductors of the cord circuit CC; it connects the busy-test lead 227 to the tip of the local plug LP; it connects the split conductor 228 to split relay 107 of the cord circuit; and it connects the ring-start lead 226 to ring-start relay 104. At the normally closed contacts controlled by the lower armature of relay 106, the bridge across the strands of the cord circuit CC by way of resistor 114 is opened, and the strands on the 25 cord are now bridged only by the common tip and ring conductors 223 and 224, contacts of feed relay 203, secondary windings of the induction coil IC, and the artificial line AL. The line relay 404 of the trunk circuit TC2 is held operated for 30 the time being through the bridge just traced.

35 The operator may now converse with the calling main-exchange subscriber over the cord circuit CC and the trunk line T2 and ascertain with whom connection is desired.

40 It is to be noted that the operator's receiver R, instead of being directly associated with the secondary windings of the induction coil C (in the usual anti-sidetone arrangement involving the artificial line AL), is replaced in this circuit by the primary winding of repeating coil RC, 45 whose secondary winding leads to the receiver R. The primary winding of the repeating coil RC is shunted by a full-wave dry-disc rectifier 210, which is so proportioned with respect to the voltages normally applied to it during conversation that it acts as a high-resistance shunt normally, but acts as a low resistance shunt in the event of the momentary application of a high voltage surge. The operator is thus protected in a large 50 measure from loud, disagreeable noises which are otherwise produced occasionally in her receiver.

55 It may be pointed out that the transmitter T obtains its energizing current from the condenser-shunted retard coil 209, and is in circuit with the primary winding of the induction coil IC.

60 Assuming that the operator learns that the calling subscriber desires to be connected with the subscriber at substation B, accessible by way of the line jack LJ2, the operator may follow either of two procedures, depending upon the operating instructions which she has received:

65 (1) She may forego the usual voluntary busy test and insert the local plug LP straightway into the line jack LJ2 of the line of the subscriber at substation B; or

70 (2) She may first make a busy test by touching the tip of the local plug LP to the sleeve of the line jack LJ2.

Testing the called line

75 It is to be noted that busy-test relay 206 has one terminal thereof connected to the negative or grounded pole of the exchange battery, while

- the other terminal thereof is connected by way of busy-test conductor 227, contacts of the operated connect relay 106, and contacts of switching relay 102, to the tip of the local plug LP of the cord circuit CC. In the event that the operator is instructed to make a tip busy-test, she places the tip of the plug LP in contact with the exposed portion of the sleeve of the line jack LJ2. In the event that the line of substation B is idle at this time the test or sleeve conductor 121 thereof has a negative potential thereon, through the usual cut-off relay (not shown), and busy-test relay 206 therefore does not operate. On the other hand, if the line of substation B is engaged, there is a ground potential on sleeve conductor 121 thereof with the result that busy-test relay 206 operates over sleeve conductor 121. At its inner contacts, relay 206 closes a circuit for the ticker relay 205, while at its lower armature it places a shunt around the resistor 207 so as to increase the amplitude of the signalling tone at this time. When ticket relay 205 operates (in series with resistor 211), it closes a shunt around its winding at its inner armature, which brings about a deenergization of the relay. Relay 205 therefore operates somewhat after the fashion of a buzzer, but less rapidly because its operation is delayed by the presence of the copper collar around the armature end of its core and the indicated copper sleeve over the entire part of the core beneath the winding, while its restoration is further delayed by the retarding effect of its winding when short circuited at the inner lower contacts of the relay.
- 35 The intermittent operation of relay 205, while its circuit is maintained closed at the inner lower contacts of busy test relay 206, results in the intermittent closure of a circuit at the lower contact of relay 205 through the lower contacts of relay 40 206 and resistor 208 for the tertiary winding of the induction coil IC. The current-flow induced in the secondary winding of the induction coil IC by this intermittent closure of the circuit through the tertiary winding of the coil, results 45 in the application of a tone signal to the operator's receiver, which tone signal may also be heard by the calling subscriber. This tone signal is interpreted as an indication that the line of substation C is in use.
- 50 When the tip of the plug LP is removed from the sleeve of the jack LJ2, busy test relay 206 restores and terminates the intermittent operation of the ticker relay 205.
- Assume now that the operator is instructed to 55 plug into the jacks of called line without first making a tip busy test. Under this condition she inserts the plug LP of the cord CC into the jack LJ2 without previously determining whether the connected line is busy or idle. Nevertheless, the 60 operator does not establish a telephonic connection with the line (when it is busy), for the tip and ring strands of the plug LP are open at contacts of switching relay 102, and the controlling, 65 idle-test relay 101, having its lower terminal connected to ground through contacts of cut-off relay 109, requires an idle-indicating potential on the sleeve conductor 121 of the jack LJ2 for its operation. Therefore, busy-test relay 206 remains connected to the tip of the plug LP. Since the line 70 of substation B is in use at this time, the potential applied to either of the talking conductors thereof is somewhere between the potentials existing at the two poles of the exchange battery (due to the 75 bridged condition of the line and the potential

drop in the usual battery-feed bridge (not shown)). As a result, busy-test relay 206 is operated over the tip of the line jack LJ2 and causes the busy tone to be applied by bringing about an operation of ticker relay 205, as above described. 5 The operator is therefore notified that the line of substation B is in use and that she should remove the plug LP from the jack LJ2.

It may be pointed out at this time that the impedance of the busy test relay 206 is made very 10 high with respect to the impedances normally obtaining in connection with subscribers' lines, whereby a dialling operation, if occurring at this time over the busy line, is not interfered with, and the automatic switching mechanism being operated continues to operate without interference.

When the plug LP is withdrawn from the jack LJ2, busy test relay 206 restores and ticker relay 205 ceases to operate.

Offering an incoming call to a busy line 20

In the event that the operator desires to make a talking connection with the line of substation B and inquire of the subscriber at substation B whether or not he cares to abandon the local connection in which is engaged and accept the incoming call, the operator restores her talking key K1 of the cord circuit CC and employs the offering plug OP to make connection with the desired busy line through the line jack LJ2. 30

When the talking key K1 is restored, connecting relay 106 restores and reestablishes the supervisory bridge through resistor 114. The guard relay 201 in the position equipment PE, which has also maintained the talking conductors of the 35 offering plug OP disconnected, restores and reconnects these conductors to the operator's headset conductors.

When the offering plug OP is inserted into the jack LJ2, the operator is placed in telephonic 40 communication with the line of substation B through the tip and ring conductors of the plug OP and the corresponding conductors of the line jack LJ2. The lower winding of tone relay 202 is energized at this time over the grounded sleeve 45 conductor 121 of the line jack LJ2 to operate the ticker relay 205 and thereby apply the tone signal to the operator's receiver and to the operator's headset conductors, thereby warning the subscriber at substation B immediately that his conversation may now be heard by the branch-exchange operator. The tone produced at this time by the above described operation of ticker relay 205, although noticeable, is sufficiently mild that conversation is not materially interfered with. 50 Therefore, the branch exchange operator can now converse with the subscriber at substation B and inform him that she is holding an incoming call for him.

In the event that the two local subscribers to 60 the conversation replace their receivers and the operator withdraws the offering plug OP from the local jack LJ2, tone relay 202 restores and ticker relay 205 ceases operating when the offering plug OP is removed from the jack PJ. Moreover, the line of substation B is freed and brought to its 65 normal idle condition responsive to the receivers being replaced at substation B and the other substation included in the previously established 70 connection.

The operator now inserts the local plug LP of the card CC into trunk jack TJ, whereupon idle-test relay 101 is operated over the sleeve of the jack LJ2, conductor 121, and the usual cut-off 75

relay (not shown) to the negative pole of the exchange battery. The line of substation B is caused to test busy to the automatic switches having access to it by the ground potential applied thereto through the winding of idle test relay 101. Relay 101 operates switching relay 102 to close the talking circuit to the line of substation B and to disconnect the busy test conductor from the tip conductor of the plug LP. Switching relay 102 also closes a lighting circuit through contacts of answering supervisory relay 105 for supervisory lamp 126, while at its inner upper armature it prepares a circuit by way of contacts of relay 108 for cut-off relay 109.

15 The operator now operates the talking key K1 again, again operating connect relay 106 along with guard relay 201, thereby again associating the position equipment PE with the cord circuit CC and again bringing the operator into telephonic communication with the calling main exchange subscriber.

In order to signal the subscriber at substation B, the operator momentarily actuates the common ring start-key K2, thereby applying ground potential to ring-start conductor 226, closing a circuit through contacts of connect relay 106 for the lower winding of individual ring-start relay 104. Ring-start relay 104 locks itself through its upper winding by way of contacts of relays 103 and 102, and contacts of the key K1. At its upper and lower armatures, ring-start relay 104 opens the talking strands and connects the ringing circuit through the plug LP to the called line. The tip conductor is now connected to the ringing-current-supply conductor 110, while the ring conductor is connected through the winding of ring-trip relay 103 to the ungrounded negative pole of the exchange battery. Ringing current is now applied intermittently in the usual manner to the line of substation B. The condenser 125, shunted around the upper armature and resting contact of ring-start relay 104, is of sufficient size to permit a small amount of ringing current to pass back to the right-hand end of the cord circuit CC, serving as an indication both to the calling subscriber and to the operator that the called subscriber is being signalled.

50 The operator is expected to restore her key K1 as soon as she has started the ringing operation and has heard the ringing-tone indication above mentioned. This brings about the restoration of connect relay 106 and guard relay 201.

When the subscriber at substation B responds 55 to the applications of ringing current by removing his receiver, the direct-current bridge thereby closed across the conductors of his line results in the operation of ring-trip relay 103. The locking circuit of ring-start relay 104 is opened by relay 103, whereupon relay 104 restores thereby opening the ringing circuit and reclosing the talking strands of the cord. Answering-supervisory relay 105, whose lower winding is connected in series with the lower talking 60 conductor of the cord circuit CC, now operates over the line of substation B in series with line relay 404 in the trunk circuit TC2 and in shunt of the supervisory-bridge resistor 114. At its inner upper armature, relay 105 closes a locking 65 circuit for itself through contacts of key K1, and contacts of the operated switching relay 102. At its lower armature, relay 105 shunts its lower winding to provide a better talking circuit, while at its upper armature it disconnects supervisory 70 lamp 126. Answering supervisory relay 105 opens 75

the previously existing supervisory bridge through resistor 114, thereby placing line relay 404 of the trunk circuit TC2 under the direct control of the called line.

The two subscribers may now converse with 5 each other as desired.

Transfer service during an incoming call

In order to explain how the transfer service operates during an incoming call, it will be assumed that the subscriber at substation B desires to obtain further information on some point under discussion before completing his conversation with the calling main exchange subscriber. In this event, the subscriber at substation B 10 momentarily operates his push button P2, thereby momentarily applying ground potential to one of the conductors of his line to bring about a momentary unbalanced current flow through the windings of the differential transfer-control relay 411. As a result, transfer relay 410 is operated through its first step when the push button P1 is pushed and is operated through its second step when push button P2 is released. The line of substation B is thereupon transferred 15 from the trunk T2 and over conductors 413-415 to the line switch LS4, which line switch operates in the usual manner to seize an idle selector such as S1. The subscriber at substation B now 20 proceeds to set up the desired connection and 25 obtain the desired information.

After the information has been obtained the local subscriber again operates the push button P1 momentarily, whereupon transfer-control relay 411 in the trunk circuit TC2 is again 30 momentarily actuated. By the resulting operation of unlock relay 409 at this time, transfer relay 410 is restored and relay 409 restores shortly thereafter. The connection between the subscriber at substation B and the calling main 35 exchange subscriber is thus reestablished, while the line switch LS4 is disconnected.

Transferring an incoming call to another local line

In the event that the subscriber (at substation B) to whom the incoming call has been directed decides that some other branch exchange subscriber (the subscriber at A, for instance) should take over the call, he may signal the branch exchange operator and request her to transfer the 40 incoming call.

In order to signal the branch exchange operator, the subscriber at substation B operates his calling device, preferably in accordance with some 45 digit greater than 5. As a result, a number of interruptions are produced in the circuit of line relay 404 of the trunk circuit TC2. Each time its circuit is interrupted, relay 404 restores and applies ground potential to conductor 426 but it 50 does not interrupt the answering bridge across the conductors of the trunk T2, for hold relay 408 (operated because this is an incoming call) holds the bridge closed. Each time it applies ground potential to conductors 426, line relay 404 closes 55 a circuit through the sleeve of the trunk jack TJ and the sleeve of trunk plug TP for the supervisory and release-timer relay 108. Relay 108 operates the first time its circuit is closed. When it does so it closes a local circuit for its upper 60 winding, rendering itself slow-releasing. Therefore, relay 108 is maintained operated throughout the dial-produced series of deenergizations of relay 404, by the slow-acting effect produced by the local circulating current in the upper winding 65 70 75

of the relay. The somewhat momentary operation of relay 108 (during the transmission of the series of impulses) results in the corresponding closure of a circuit for supervisory lamp 126 at armature 129. Lamp 126 therefore becomes lighted for a moment to attract the operator's attention.

The weighted spring 127 is struck by the associated armature, but the contact produced by this action is an unsteady vibrating contact preferably for a period of substantially more than a second, with the result that the vibrating spring 127 does not come to rest (to thereby allow the upper winding of relay 109 to become energized) during the somewhat momentary interval that relay 108 is held operated responsive to the succeeding impulses of the recall series. Relay 109 is somewhat slow to operate, as indicated, for which reason it does not respond in any event to the operation of relay 108 until the vibration of the weighted spring 127 has substantially ceased.

When relay 108 restores, upon the cessation of the impulses, lamp 126 becomes extinguished.

The above signalling operation may be repeated as often as desired, or until the operator responds.

The operator responds to the above lighting of supervisory lamp 126 by throwing her key K1 to talking position, bringing about the reoperation of connect relay 106 and guard relay 201. The operator may converse with the local subscriber and discover to whom the call should be transferred, which transfer operation is carried out by removing the plug LP from the local jack and by proceeding to make connection with the line of substation A through jack LJ1. When the plug LP is removed from the jack LJ2, idle-test relay 101, switching relay 102, and answering supervisory relay 105 restore successively, placing the cord circuit in condition for making a new connection. Line relay 404 is held operated, during the transfer of the plug LP, through the operator's headset conductors, and resistor 114 is again in readiness to bridge the cord to hold the line relay 404 after the operator restores her talking key and pending the response of the subscriber at substation A, to whose line the call has been transferred.

The testing of and signalling over the line of substation A take place as described for the line of substation B.

When the subscriber at substation A replies, answering supervisory relay 105 is again operated to extinguish lamp 126 and to open the temporary holding bridge through resistor 114.

Clearing out the incoming connection

When the inter-exchange conversation is completed, the calling main exchange subscriber and the local branch-exchange subscriber replace their receivers. When the receiver is replaced at substation A, line relay 404 in the trunk circuit TC2 restores and opens the circuit of release relay 405, permitting relay 405 to restore after a slight interval. Hold relay 408 is unlocked by release relay 405. Disconnect supervision is given to the main exchange at the upper contacts of hold relay 408. With release relay 405 restored, conductor 423 is ungrounded to mark the trunk T2 idle at the selectors such as S1.

Line relay 404 also applies ground potential to sleeve conductor 426, thereby closing a circuit through the sleeve of the jack TJ of the plug TP for supervisory relay 108. Relay 108 operates and at armature 129 closes a circuit for supervisory

lamp 126, which lamp becomes lighted as a disconnect signal. At the same time, a circuit for the upper winding of cut-off relay 109 is closed through the weighted-spring contact of relay 108, inner upper armature of switching relay 102, and contacts of key K1. Cut-off relay 109 is therefore operated after an interval of somewhat more than one second has elapsed, during which interval the weighted spring of contact 127 goes through its period of vibration. Upon operating, relay 109 locks its lower winding to the sleeve of the plug PT, at the same time opening the talking strands of the plug TP. At contacts controlled by the middle lower armature, relay 109 removes ground potential from one terminal of idle-test relay 101, thereby freeing the line of substation B and permitting idle-test relay 101 and switching relay 102 to restore. At its upper armature, switching relay 102 opens the initial circuit of cut-off relay 109, but cut-off relay 109 is now maintained operated in the locking circuit including its lower winding and the sleeve conductor of the plug and jack. Answering supervisory relay 105 is also restored by the opening of the inner upper contacts of relay 102.

Answering supervisory relay 105, at its lower armature, again bridges the resistor 114 across the strands of the cord circuit CC, but this does not result in a reoperation of line relay 404 of the trunk circuit TC2, because the tip and ring conductors of the trunk plug TP are disconnected at contacts of cut-off relay 109.

It is to be particularly noted that both the line of substation B and the trunk circuit TC2 are freed for further use, even though the operator permits the plugs LP and TP of the cord circuit CC to remain in the jacks LJ2 and TJ indefinitely.

When the operator removes the plugs LP and TP, relays 108 and 109 in the cord circuit CC restore, returning the cord circuit to normal condition, supervisory lamp 126 being extinguished at armature 129 of relay 108.

In the event that the trunk line T2 is seized at the automatic switchboard in an outgoing call while the plug TP is still in the trunk jack TJ, and the local plug LP is still in the local jack LJ2, jack-cut-off relay 412, upon operating in series with conductor 421 upon the seizure of trunk circuit TC2, places ground potential directly on conductor 426 at its lower armature so as to maintain relay 109 of the cord circuit CC actuated after line relay 404 has operated responsive to the seizure.

Conductor 426 is thus maintained grounded at jack-cut-off relay 412 for the duration of the outgoing call, and ground potential is reapplied to this conductor by line relay 404 at the termination of the call before jack-cut-off relay 412 is permitted to restore.

In the event that an incoming call is received over the two-way trunk T2 while the trunk plug TP still is in the trunk jack TJ and the local plug LP is still in a local jack, the call lamp 124 at the jack TJ is lighted in the usual manner over conductor 428 when call relay 407 responds to the actuation of ring-up relay 406. Upon noting the lighted condition of the call lamp 124, the operator first removes the local plug LP from the local jack and then momentarily removes the trunk plug TP from the trunk jack TJ, again inserting the plug in the jack. The momentary removal of the trunk plug TP from the jack TJ, permits relays 108 and 109 to restore, and relay 109 is thus permitted to again connect up the talking conductors of the plug TP to the cord. There-

fore, line relay 404 is operated when the plug is reinserted, removing ground potential from conductor 426, and otherwise operating as hereinbefore described.

5 From the foregoing, it will be seen that the operator need be in no particular hurry to remove her cord circuit after an incoming conversation through a cord circuit has been completed, in the event that she is for the moment engaged in 10 other duties.

Offering an incoming call to an idle line

Since the cord CC is a "dry" cord (it contains no current-supply bridge), special arrangements 15 must be made to furnish talking current to the called local line in the event that the operator desires to converse with the local called subscriber without the knowledge of the calling main exchange subscriber, ordinarily for the purpose of determining whether or not the tentatively selected local subscriber is the one to take 20 the call.

In order to split the cord CC, the operator (with the talking key K1 and connecting relay 106 in 25 the cord operated, together with guard relay 201 of position equipment PE) operates the common key K2 to split position, in which position the left-hand contacts of the key are actuated. The lower contacts of the split key place ground potential on split conductor 228, closing a circuit 30 through contacts of operated relay 106 for split relay 107 in the cord circuit. Relay 107 bridges the dial conductors 229 and 230 across the tip and ring conductors of the trunk plug TP, to hold the 35 line relay of the connected trunk in operated condition. At the same time, the talking strands of the cord circuit are separated at the contacts of relay 107, whereby the telephonic connection with the calling main-exchange line is severed.

40 The local line reached through the plug LP is now deprived of its previous supply of energizing current for the transmitter. Therefore in the position equipment PE contacts of the split key K2 operate the feed relay 203 to connect the 45 retard bridge 204 across the operator's tip and ring conductors 224 and 223 as a transmitter-supply bridge for the local line, at the same time inserting condensers between conductors 223 and 224 and the operator's telephone equipment, it 50 being unnecessary to send transmitter current through the secondary winding of the induction coil IC.

The operator now proceeds to converse with the local subscriber and determine whether or not 55 he is the one to take the incoming call. It is to be noted that the upper contacts of the split key K12 disconnect the upper winding of tone relay 202 from tone conductor 225, so that this tone relay is not operated at this time to place a warning tone on the operator's headset conductors and the conductors of the called local line. This 60 warning tone is obviously unnecessary now, as the conversation is only between the operator and the local subscriber.

65 Assuming that the called local subscriber is the one to take the call, the operator restores the talking key K1 and split key K2. Feed relay 203 in the position equipment PE restores, as does split relay 107 in the cord circuit CC.

70 The two subscribers may now converse through the cord circuit CC.

Putting through a delayed call

The way in which a delayed outgoing call is 75 handled by the branch exchange operator will

now be explained. For this purpose it will be assumed that the subscriber at substation A, being unable to reach a desired main exchange subscriber, requests the switchboard operator to make an attempt to set up the connection for him, such 5 a call being termed a delayed call. To complete the delayed call, the branch exchange operator inserts the trunk plug of an idle cord, the trunk plug TP of the cord circuit CC, for example, into a trunk jack, such as TJ, associated with a two-way trunk which is idle, the busy or idle condition being indicated by the lighted or unlighted condition of the busy lamp 123, associated with jack TJ.

When the plug P is inserted into the jack TJ, 15 line relay 404 of the trunk circuit TC2 energizes as previously pointed out, in series with resistor 114 bridged across the strands of the cord circuit CC. Release relay 405 applies ground potential to conductor 423 to guard the trunk circuit 20 TC2 against seizure at the automatic switchboard. At its upper contacts line relay 404 closes a bridge across the conductors of the trunk T2 through the left-hand windings of repeating coil 403 and resistor 413, thereby signalling the main 25 exchange operator in the event the main exchange is a manual exchange, or taking a first selector for use in the main exchange in the event that it is an automatic exchange. The throwing of the key K1 into talking position associates the position equipment PE with the cord circuit CC, so that the branch exchange operator may converse with the main exchange operator and request the number she wants.

Setting up the delayed connection when the main exchange is an automatic exchange 35

For the purpose of explaining the dialling feature of the position equipment PE, the cord circuit CC, and the trunk circuit TC2, it will be assumed now that the main exchange is an automatic exchange, in which event the operator must control the transmission of dialling impulses to bring about the setting of the automatic switching apparatus on the terminals of the desired main exchange line.

With the key K1 operated in the cord circuit CC, the operator actuates the key K2, Fig. 2, to split position, thereby placing ground potential on split conductor 228. As a result split relay 50 107 in the cord circuit CC is operated through contacts of connect relay 106. In addition to disconnecting the lower winding of supervisory relay 108, relay 107 connects dial-tip and dial-ring conductors 229 and 230 to the tip and ring conductors of the trunk plug TP, at the same time disconnecting the two plugs of the cord from each other to prevent dialling interference from the local plug in the event that the operator has already made connection to the local line. The line 60 relay 404 of the connected trunk circuit TC2 is now held operated over the dial-tip and dial-ring conductors 229 and 230, through contacts of the actuated split relay 107, resistor 235 in the position equipment PE, and impulse contacts 65 232 of the calling device 231.

When the operator actuates the dial (not shown) of the calling device 231 from its normal position pursuant to the dialling of the first digit, off-normal contacts 233 and 234 close. Off-normal contacts 233 shunt the associated resistor 235 so as to form a better dialling circuit for relay 404 in the trunk circuit TC2, while off-normal contacts 234 apply ground potential at a second point to split conductor 228, so as to in- 75

variably maintain the split relay 107 operated until the calling device reaches normal position. This latter feature is of utility in the event that the operator, upon the dialling of the final digit, 5 restores her split key before the calling device completes the transmission of the final digit.

As the calling device 231 returns to normal, the impulses are transmitted by the predetermined 10 number of momentary separations of impulse contacts 232, which contacts are shunted by the usual spark suppressor condenser and associated resistor, as shown.

After she has completed dialling the desired 15 number, the operator restores the key K2, bringing about the restoration of split relay 107 to terminate the split condition of the cord circuit CC.

Assuming now that the desired main exchange 20 subscriber responds, the operator may request him to wait a moment while she gets in touch 25 with the subscriber at substation A. This she does by inserting the local plug LP in the line jack LJ2 and momentarily operating the ring-start key K2 to bring about the operation of ring-start relay 104. Relays 101 and 102 operate responsive to the insertion of the plug LP into the 30 jack LJ2 to prepare the talking circuit, while the ring-start relay 104 starts the operation. From this point the operations are as hereinbefore described.

Night service

In order to provide for the reception of calls 35 incoming to the branch exchange by such subscribers as are on duty at night or at other times when the branch-exchange switchboard is unattended, the trunk T2 may be extended directly to a branch-exchange line, the line of substation B, for example. This extension is made through a cord circuit, the cord circuit CC, for 40 example. In this event, the key K1 is actuated to night position and the trunk plug TP is inserted into the night jack NJ, Fig. 4, while the local plug LP is inserted into the jack LJ2.

The upper contacts of jack NJ ground conductor 45 423 to guard the trunk against seizure at the automatic switchboard. With the plug LP in jack LJ2, idle test and switching relays 101 and 102 are actuated, as in a standard call to the local line. Moreover, answering supervisory relay 105 is held continuously operated 50 at contacts of the night key, whereby the resistor 114 is not in bridge of the talking strands of the cord, and lamp 126 is maintained extinguished.

Henceforth, each time an incoming call is received over trunk T2, ringing current passes through jacks NJ and LJ2 by way of cord circuit CC to the line of substation B. such incoming calls, therefore, may be answered directly at B. 55 Moreover, when he desires to do so, the subscriber at B may make an outgoing call directly over the trunk T2, which has been rendered individual to his line as above described.

When desired, the operator may inform the 60 subscriber at substation B when his line is about to be converted to the night condition. For this purpose, before placing the plug TP into the jack NJ, the operator places the plug LP into the jack LJ2; operates the talking key; momentarily 65 operates common key K2 to ring-start position to start the ringing operation; and then operates K2 to split position to cause feed relay 203 to operate and connect up retard 204 as a transmitter-supply bridge for use when the called 70 subscriber responds.

After the subscriber responds and acknowledges the information, the operator restores K2; actuates K1 to night position; and inserts plug LP into night jack NJ.

The upper contacts of the night section of key 5 K1 open the locking circuit of ring-start relay 104 to restore this relay in the event that the subscriber at substation B does not respond, while the middle contacts of the key separate the circuits of relays 105 and 104 to prevent the 10 operating potential applied to the upper winding of relay 105 from driving a holding current through relay 104.

What is claimed is:

1. In a telephone system, lineswitches terminating subscriber lines, respectively, other lineswitches, links accessible to all said lineswitches, means responsive to the removal of the receiver on a subscriber line for operating the associated lineswitch to take one of the links for use, means 15 for extending a connection from the seized link to a desired called line, a transfer link included in the extended connection or not depending upon the line called, one of said other lineswitches being individual to said transfer link, 20 and means controlled at will over the line of the calling subscriber in the event that the extended connection includes said transfer link for severing the distant end of the transfer link and for operating the associated lineswitch to extend 25 the calling line by way of the near end of the transfer link and the associated individual lineswitch to another one of the first named links.

2. In a telephone system, lineswitches terminating subscriber lines, respectively, other lineswitches, links accessible to all said lineswitches, means responsive to the removal of the receiver on a subscriber link for operating the associated lineswitch to take one of the links for use, means 30 for extending a connection from the seized link to a desired called line, a transfer link included in the extended connection or not depending upon the line called, one of said other lineswitches being individual to said transfer link, 35 and means controlled at will over the line of the calling subscriber in the event that the extended connection includes said transfer link for severing the distant end of the transfer link and for operating the associated lineswitch to extend 40 the calling line by way of the near end of the transfer link and the associated individual lineswitch to another one of the first named links, and means subsequently controlled at the will of the calling subscriber for freeing the link taken for use by way of the last-named lineswitch and for 45 reconnecting the severed portion of the transfer link.

3. In a telephone system, two groups of serially related link circuits for use in setting up telephone connections between subscriber lines, a 50 group of subscriber lines, each line extending to a lineswitch having access to links of the first group, switching apparatus for extending a seized link of the first group to a link of the second group, each link of the second group having 55 a normally connected branch and a normally disconnected branch, each of said normally disconnected branches extending to a lineswitch having access to links of the first group, and means controlled at will over the line of a calling subscriber when a connection has been set up therefore through one of the links of the second group for disconnecting the normally connected branch and for connecting the normally disconnected branch to cause the associ- 60 70 75 80 85 90 95 98 99 100

ated lineswitch to operate and extend the calling line to a second link in the first group.

4. In a telephone system, a trunk line extending from a first exchange to a second exchange, said trunk line having a first branch in the first exchange normally connected thereto and a second branch normally disconnected from the trunk line, switching apparatus in the first exchange for extending a connection from a subscriber's line to said trunk line by way of the first branch, an automatic switch terminating the second branch, and means controlled at will over the subscriber line for substituting the second branch for the trunk line to extend the subscriber line to said automatic switch and subsequently controlled at will over the calling line for substituting the trunk line for the said second branch.

5. In a telephone system, a trunk line extending from a first exchange to a second exchange, said trunk line having first, second, and third branches in the first exchange, switching means in the first exchange for connecting a subscriber line with the trunk line by way of the first branch, switching means for connecting a subscriber line with the trunk line by way of the second branch, an automatic switch terminating the first branch and means controlled at the will of the subscriber on a line connected with the trunk line by way of either the first branch or the second branch for substituting the third branch for the trunk line to connect such subscriber line with the automatic switch, and subsequently controlled at will for substituting the trunk line for the said third branch.

6. In a telephone system, a trunk line having a first branch and a second branch at one end thereof, means for connecting a subscriber line with said trunk line by way of the first of said branches, a supply bridge in said trunk line for supplying transmitter current to the connected subscriber line, a differential control relay in the first branch non-responsive to the normal balanced flow of current over the subscriber line, means at the substation on the subscriber line for temporarily unbalancing the flow of transmitter current to bring about an operation of said control relay, means responsive thereto for substituting the second branch for the said trunk line, means in the second branch for supplying a flow of transmitter current, and means responsive to a further operation of said control relay in the event that the flow of transmitter current therethrough from the second branch is subsequently unbalanced at the station on the subscriber line for substituting the trunk line for the said second branch.

7. In a branch telephone exchange trunk-connected with a main exchange, an automatic switchboard and a manual switchboard, means at the automatic switchboard for completing local connections and for setting up connections to the main exchange by way of the interconnecting trunk lines, means at the manual switchboard for completing incoming connections from the trunk lines to the local lines, means effective in the event of a connection incoming from the main exchange or of a connection outgoing to the main exchange for enabling the local subscriber at will to transfer the connection temporarily from the main exchange to another local line, and subsequently back to the main exchange again, and means controllable by the operator through the manual switchboard responsive to a signal from the local subscriber for transferring an incom-

ing connection from the local line originally connected with to a desired other local line.

8. In a combined automatic and manual branch exchange trunk-connected to the main exchange, means including a cord circuit at the manual switchboard for interconnecting an incoming trunk line with a local line to complete an incoming connection, a transfer relay in the trunk line, a supervisory relay and a cut-off relay in the cord circuit, and means selectively controlled over the called line for actuating the said relays.

9. In a branch exchange trunk-connected with a main exchange through two-way trunk lines, an automatic switchboard through which local connections may be made and connections through which outgoing to the main exchange over said trunk lines may be made, a manual switchboard, an extension from each two-way trunk line to the manual switchboard to enable incoming connections to be completed therethrough to the local lines, and means effective when a two-way trunk line is seized at the automatic switchboard to complete an outgoing connection for disconnecting the manual-switchboard extension of such trunk line.

10. In a telephone system, trunk lines extending to a manual switchboard, subscriber lines extending from the manual switchboard, means including a double-plug cord circuit at the manual switchboard for interconnecting a subscriber line with a trunk line, and means automatically effective when the subscriber on the interconnected line replaces his receiver after the termination of a conversation for disconnecting both plugs of said cord circuit to thereby free the subscriber line for further use and to free the trunk line for further use while the plugs of the cord circuit remain in place.

11. In a telephone system, a manual switchboard having cord circuits through which desired connections are extended, the talking strands of the calling plug of each cord circuit being normally open, means dependent upon the called line being in an idle condition for closing the calling strands of the cord circuit, and means including an offering cord and plug forming an extension of the operator's headset conductors for enabling the operator to make connection with a busy line to offer a call.

12. In a telephone system, a plug ending cord having the tip and ring conductors normally open, a busy-test relay normally connected to the tip of the plug, and relay apparatus operable over the sleeve of a jack into which the plug is inserted for disconnecting the busy-test relay and for closing the tip and ring conductors, depending upon an idle condition of the line associated with the said jack.

13. In a telephone system, a plug ending cord having the tip and ring conductors normally open, a busy-test relay normally connected to the tip of the plug, relay apparatus operable over the sleeve of a jack into which the plug is inserted for disconnecting the busy-test relay and for closing the tip and ring conductors, depending upon an idle condition of the line associated with the said jack, and means controlled by the busy-test relay when the line associated with the jack with which the plug is brought into engagement is busy for placing a busy-tone potential on the cord.

14. In a combined automatic and manual branch exchange trunk-connected to the main exchange by two-way trunks appearing both at the automatic switchboard and at the manual

switchboard, subscriber lines appearing at both switchboards, an operator's cord circuit for completing connections between trunk lines and local lines, and means in said cord circuit effective when the operator plugs into one of said lines and when she plugs into one of said trunks for

preventing intrusion upon a busy connection if one is taking place and for preventing interference with the transmission of switch settling impulses in the event that an automatic connection is being set up.

JOHN H. VOSS.
